Inventor:

John Lane.

UNITED STATES PATENT OFFICE.

JOHN LANE, OF HYDE PARK, ASSIGNOR TO THE PERU CITY PLOW COMPANY, OF PERU CITY, ILLINOIS.

CULTIVATOR.

SPECIFICATION forming part of Letters Patent No. 275,502, dated April 10, 1883.

Application filed November 2, 1882. (No model.)

To all whom it may concern:

Be it known that I, JOHN LANE, of Hyde Park, in the county of Cook and State of Illinois, have invented a new and useful Improvement 5 in the Construction of Cultivators, which improvement is fully set forth in the following specification and accompanying drawings.

This invention relates to that class of cultivators in which the shovels are attached to beams jointed at their forward ends to a wheeled draft-frame in such a manner that they may be moved horizontally to follow the rows of corn and moved vertically to throw them into and out of action, and particularly to an improvement 15 proved spring attachment designed to raise or assist the operator in raising the beams above an operative position without interfering with their lateral motion when in action. The arrangement is designed so that when the beams are in an operative position they will be subject to little or no lifting strain, and when the beams are being moved upward the spring will exert an increasing lifting strain as they go upward toward the position of suspension.

The invention consists in mounting on the frame of the cultivator, above the horizontal ends of the axle, a spring having a connection with an arm depending from the sleeve, and in certain combinations of parts, which will first be described, and afterward pointed out in the claims, as follows:

The attachment is applicable to any and all cultivators in which the beams have a vertical and lateral motion, but is designed more particularly for use in connection with what is known in the art as "walking straddle-row" cultivator, in which an arched axle is provided at its ends with supporting-wheels and with couplings, to which the plow-beams are attached.

Referring to the drawings, like letters refer to like parts in all the figures. Figure 1 represents a side elevation view of a cultivator, with my improvements shown applied to one side only, the two sides being in practice the duplicate of each other, as usual, showing the shovels in position for working. Fig. 2 also represents a side elevation view of same, showing the shovels in an elevated position. Figs. 3 and 4 are perspective views of detail parts.

A represents the axle, having its central portion arched upward, with sides *a* and with horizontal ends *b*. B represents the supporting-wheels, applied to the horizontal ends of the axle; C, the draft-pole or tongue, and D one of the two plows. The plow-beam has its forward end provided with a coupling-head, pivoted on the bolt *c*, and the coupler *d*, clasping the sleeve *E*, mounted loosely around the end of the axle. The bolt *c* permits the plow-beam to swing laterally, while the rotating of the sleeve upon the axle permits it to swing vertically, in order to throw the shovels into and out of the ground. The above parts are of ordinary construction, and form no part of my invention.

The sleeve *E* is provided with an arm, *e*, depending from the sleeve, extending downward nearly perpendicular and nearly or about at right angles with the plow-beam, as shown, and the outer end of the said arm may have a perforation, *p*, to receive a connection with the spring.

To the side *a* of the axle I attach a bracket, *F*, which has a perforation, *f*, as shown, in which perforation is seated one end of the spring *S*, and the other end of the spring is connected to the end of the depending arm *e*, as shown. The spring *S*, I preferably make of round bar-steel, bent in a somewhat spiral form, and increasing in diameter with each round of bend, and the outer end may extend to the end of the arm *e*, as shown in Fig. 1; or, a link, *g*, may be intermediate between the spring and arm, as shown in Fig. 2. The operation of the spring *S* is exerting a lifting strain upon the depending arm *e*, as will be hereinafter more fully explained. Any other known construction of the spring operating with a lifting strain may be substituted without departing from my invention.

When the parts are in an operative position, as shown in Fig. 1, the perforation *p* in the arm *e*, the ends *b* of the axle, and the perforation *f* in the bracket *F* stand in a line or substantially in a line with each other, the center of motion of the sleeve *E* being on a line between the two ends of the spring as a "dead-lock," so that the spring has little or no effect lifting upon the plow-beam. When,

however, the beam is elevated, which will move the sleeve E around on the axle, carrying the arm e so as to move the perforation p out of the line above described, the spring will then 5 exert a lifting strain to revolve the sleeve and carry the plow-beam upwardly, and as the beams go upward the perforation p in the arm e increases in distance out of line, and thereby 10 the spring has more leverage for rotating the sleeve and lifting the plows.

The spring may be of sufficient strength to effect the lifting of the plow and its suspension without any assistance on the part of the operator other than to start the plow in its upward going, moving the perforation p of the arm e out of the dead-lock line. It will be observed that as the beam descends the lifting effect of the spring upon the beam is diminished, the action ceasing or being reduced to 15 such an extent as to be nominal by the time that the shovels enter the ground; and it will also be observed that, as the spring changes its force from that of rotating the sleeve lifting the plow to spending its force against the 20 axle in a dead-lock, the spring operates, holding the plow in suspension, as it were, in a position for active operation without either lifting 25 or bearing down on the plow.

I am aware that it is not new to provide a 30 sleeve with a depending arm to which a spring may be connected. Such I do not claim; and I am aware that it is not new to so arrange the spring and the arm that they will be as in a dead-lock above and outside of the center 35 of motion of the sleeve. Such I do not claim. In my invention the dead-lock occurs when the center of motion of the sleeve is between the two ends of the spring, as one end of the

spring is attached to the axle above the sleeve, the other end connected to the depending arm 40 below the sleeve, which in operation provides for the use of a longer spring and a better action of the parts than has heretofore been known with the spring working only above the sleeve. 45

Having thus set forth my invention, I claim—

1. In a cultivator, the combination of the vertically-swinging beam, the sleeve provided with the depending arm, the spring having one of its ends connected to the outer end part 50 of the said arm below the center of motion of the sleeve, the other end of the spring attached to the axle above the sleeve, and the spring arranged to urge upward on the depending arm, whereby when the beam is in a horizontal position the center of motion of the sleeve will be as in a dead-lock between the two ends of the spring, and the lifting force of the spring spent against the axle, all constructed and arranged to operate substantially 55 as shown.

2. In a cultivator, the arched axle, the beam connected to the axle by a coupling permitting both vertical and lateral movement of the beam, in combination with the sleeve rotary 65 on the axle, the arm depending from the sleeve extending downwardly at about right angle with the beam, the spring S, the link g, and the bracket F, all constructed and arranged to operate substantially as shown. 70

Dated at Hyde Park, Illinois, this 14th day of October, 1882.

JOHN LANE.
